UNITED STATES PATENT OFFICE.

JOHN L. ALLEN, OF MANVILLE, RHODE ISLAND.

LUBRICATOR.

1,117,542.

Specification of Letters Patent. Patented Nov. 17, 1914.

Application filed November 12, 1913. Serial No. 800,659.

To all whom it may concern:

Be it known that I, JOHN L. ALLEN, a citizen of the United States, and resident of Manville, in the town of Lincoln, in the 5 county of Providence and State of Rhode Island, have invented certain new and useful Improvements in Lubricators, of which the following is a specification.

This invention relates to lubricators of 10 the class adapted to automatically mix one material with another whereby both may be carried in a compound form to the parts to be lubricated, and the invention has for its object to provide a receptacle adapted to receive a non-liquid body, such as graphite or the like, and to locate said receptacle adjacent to a conductor through which lubricating fluids, such as oil or the like is adapted to pass, and to provide a passageway between the two through which a portion of 20 the oil in its passage through the conductor may enter the receptacle and equalize the pressure therein, and to force the graphite contained in the receptacle through said 25 passageway to be picked up by and mixed with the flowing oil and be conducted thereby to the parts to be lubricated.

A further object of the invention is to provide a valve in said receptacle adapted 30 to close said passageway without interfering with the flow of oil through the conductor whereby when the receptacle is being loaded or the cover removed for inspection or repairs, the flow of oil to the parts may continue uninterrupted.

The invention further consists in the provision of a mixing chamber communicating with the oil conductor to which the graphite may be carried and there thoroughly mixed 40 with the oil. This is found in practice to be quite important for disintegrating and breaking up by agitation, slugs or lumps of graphite which may be forced through the passageway and deposited in the oil so that 45 the graphite after being acted upon in said chamber may pass on together with the oil and properly lubricate the parts without clogging the ducts or openings.

With these and other objects in view, the 50 invention consists of certain novel features

of construction, as will be more fully described and particularly pointed out in the appended claims.

Of the accompanying drawings: Figure 1— is a diagrammatic view illustrating one 55 method of connecting my improved lubricator to the main steam supply pipe of an engine. Fig. 2— is a sectional elevation of my improved lubricator. Fig. 3— is a plan view of my improved receptacle. 60

Referring to the drawing 10 designates the receptacle for containing the non-liquid lubricant such as graphite, or the like, the same being constructed in the form of a cup open at its top and a cap 11 threaded 65 therein, the cap itself being provided with a central opening 12 into which a threaded plug 13 is fitted so that it may be readily removed to ascertain when a recharging of the receptacle is necessary without removing the main cap 11. In the drawing I have also illustrated an oil channel or passageway 14 formed in a boss 15 integral with the side of the receptacle adjacent to the chamber, the axis of this channel being substantially parallel with that of the chamber. The upper end of this boss is threaded as at 16 to receive an oil conductor pipe or tube 17, and the lower end of the boss is threaded as at 18 into which a check valve 19 of any suitable construction may be screwed through which the oil supply passes on its way to perform its lubricating function. Adjacent the bottom 20 of the receptacle I have formed a threaded opening 85 21 into the oil conducting channel 14, and into this opening I have screwed a plug 22 preferably from the inside of the chamber, said plug having a central bore or hole 23 through it, the inner end of the plug being 90 counterbored as at 24 for the purpose of forming a thin wall about the aperture through which the graphite may be forced, to prevent as far as possible this lubricant from forming into slugs which is apt to be 95 the case where it is forced through an elongated narrow passageway. In order to control this opening 23 between the receptacle chamber and the conductor I have provided a valve 25 whose axis is preferably 100

set at a right angle to that of the receptacle, the stem of the valve being arranged to pass through a bushing 26 which is screwed at 27 into the outer wall of the receptacle, said 5 stem being threaded at 28 in said bushing and its outer end passing through a packing gland 29 therein, whereby when it is desired to close the opening it is only necessary to operate the hand wheel 30 and screw the 10 valve to its seat in the plug 22, thus effectually closing the opening between the conductor and the receptacle chamber, and that without affecting or in any way interfering with the passage of the oil through said 15 conductor.

In some instances it has been found of importance to provide a mixing chamber 31 connected to the oil conducting pipe or tube whereby if the graphite should become hardened or formed into lumps or slugs, as is sometimes the case where the apparatus stands over night, it will be carried upward by the flow of oil through the conductor into this chamber where it is acted upon by 20 the moving oil and agitated, rolled about, disintegrated or broken up by the action of the flowing oil, and when so disintegrated and thoroughly mixed with the oil it passes on to best perform its lubricating function 25 30 as a compound without clogging the lubricating ducts or channels.

I have shown and described the conducting channel or passageway 14 as being formed in a boss integral with the receptacle 10, but while this is of structural advantage owing to the fact that the conductor should be placed close to the chamber, yet this construction is not necessary as the oil conductor may be of a continuous tube or 35 40 pipe formed independent of the graphite receptacle, and connected thereto through any suitable pipe or opening as at 23.

In practice my improved lubricator may be attached in any convenient manner to 45 automatically mix graphite or other non-liquid lubricant with oil and supply this mixture to the parts to be lubricated. In 50 Fig. 1 of the drawing I have shown the apparatus as connected to supply the combined oil and graphite to the main steam supply 55 pipe 31 to an engine cylinder 32. In this device the oil is placed in the cup 33 and is forced, by means of the usual pump 34 actuated from the moving parts of the engine, through the oil conducting pipe 35 up past the graphite receptacle 10. The valve 25 to the graphite chamber is now opened and a very small portion of the oil, in traveling upward through its conductor, works its 60 way in through the opening 23, and the body of graphite to the top or above the same, and so equalizes the pressure in this chamber whereby the gravity of the graphite

causes it to settle and work slowly outward 65 through this aperture where it is picked up by the flowing oil and carried on as a mixture into the main steam pipe 31.

By placing the opening at the lower end of the receptacle practically all the contents thereof may be forced out each time it is charged, and the quantity of the flow through this aperture may be nicely controlled and regulated by simply adjusting the valve 25. By my improved construction 70 it will be seen that the oil conductor is wholly on the exterior of the graphite chamber and is so arranged that the communication between the graphite receptacle and the conductor may be shut off by the valve 75 80 25 whereby the cap of the graphite chamber may be removed, for inspection or repairs and filled or recharged with graphite as often as may be desired without in any way interfering or affecting the continuous flow of oil through the adjacent conductor to the parts to be lubricated.

The device is extremely simple and practical in construction and is found in practice to be efficient, economical and reliable 90 in its operation, and by its use the desired quantity of any non-liquid lubricant may be automatically mixed with the lubricating fluid.

I claim:

1. A lubricator comprising a receptacle 95 for containing a non-liquid lubricant body, a conductor arranged parallel with the axis of said receptacle to conduct liquid lubricant past the latter, and a conduit leading through the side wall of said receptacle and discharging into said conductor.

2. A lubricator comprising a receptacle for containing a non-liquid lubricant body, a conductor arranged parallel with the axis of said receptacle to conduct liquid lubricant past the latter, and a conduit leading 105 through the side wall of said receptacle near the lower end thereof and discharging into said conductor, and a shut-off valve controlling said conduit.

3. A lubricator comprising a receptacle for containing a non-liquid lubricant body, a conductor arranged parallel with the axis of said receptacle to conduct liquid lubricant past the latter, and a conduit leading 115 through the side wall of said receptacle and discharging into said conductor, said conduit being counterbored to form a thin-walled aperture to prevent the contents of the receptacle being discharged in lump 120 form.

4. A lubricator comprising a receptacle for a non-liquid lubricant, a conductor for a lubricating fluid adjacent said receptacle, a mixing chamber communicating with said 125 conductor, a passageway near the lower por-

tion of said receptacle leading therefrom into said conductor and a valve for controlling said passageway.

5. A lubricator comprising a receptacle for graphite, an oil conducting tube located on the exterior of and adjacent to said receptacle, a passageway connecting said receptacle and tube located near the lower portion of the former through which the oil 10 may enter to mix with the graphite and the latter pass into the oil tube, a valve in said

receptacle for closing said passageway without affecting the flow of oil through said tube, and a mixing chamber in said tube above said passageway. 15

In testimony whereof I affix my signature in presence of two witnesses.

JOHN L. ALLEN.
